United States Patent Office

Des. 215,477
Patented Sept. 30, 1969

215,477

FLOOR LAMP BASE

Ralph H. Ellsworth, Willoughby, Ohio, assignor to Superior Funeral Supply Corporation, Cleveland, Ohio, a corporation of Ohio

Filed Jan. 16, 1969, Ser. No. 15,372

Term of patent 14 years

Int. Cl. D26—02

U.S. Cl. D48—20

The figure is a perspective view of a floor lamp base embodying my new design, the opposite sides not shown, being substantially mirror images of the sides shown.

I claim:

The ornamental design for a floor lamp base, as shown and described.
